UNITED STATES PATENT OFFICE.

SVEN JULIUS STRID, OF CHICAGO, ILLINOIS, ASSIGNOR TO FRED MATHEWS, OF CHICAGO, ILLINOIS.

MOUNTING FOR BRAKE GEARS.

Application filed August 5, 1925. Serial No. 48,424.

To all whom it may concern:

Be it known that I, SVEN JULIUS STRID, a citizen of the United States of America, residing at Chicago, in the county of Cook and State of Illinois, United States of America, have invented a new and useful Improvement in a Mounting for Brake Gears, of which the following is a full, clear, and exact description, such as will enable others skilled in the art to make and use the same.

My present invention relates to means for mounting a brake gearing at the end of a railway car and has particular reference to means for reinforcing the structure so that the pull of the brake chain or rods, when the brake is applied, will not displace the gearing or its housing.

In certain types of railway cars it is frequently the practice to place the brake shaft at a corner of the car and mount the same outside the car wall or sides and there is a narrow platform or ledge from which an apron or metal sheet depends. This structure is rather too flimsy and unsecure to withstand the heavy service demanded of a brake gearing and its mounting and I have, therefore, devised a structure which reinforces the corner portion of the car body adjacent the brake gear by means of an oblique angle beam extending from an end to a side of the car and to which the brake gear housing is secured. Further details of the structure will appear in the following description.

I prefer to carry out my invention and accomplish its divers objects by means of the structure hereinafter fully described and as more particularly pointed out in the claims, reference being made to the accompanying drawings that form a part of this specification.

In the drawings:

Figure 1 is a top plan of one corner of a railway car, showing the application of my improvements thereto.

Figure 2 is a vertical elevation of the lower portion and one end of the railway car, as illustrated in Figure 1, the view illustrating an end elevation of my invention.

Figure 3 is a longitudinal side elevation of my improvements and illustrating a fragmentary portion of the end of the side of the car.

The drawings, which are schematic, illustrate a typical or preferred embodiment of my invention, and in the several views I have employed similar reference characters to designate like parts wherever they appear throughout the drawings.

Referring first to Figure 3, it will be seen the end of the car body is a vertical wall 5 having a Z-shaped plate 6 secured to the outer face thereof, said plate being so arranged that the parallel members thereof are vertically disposed and the transverse member of the plate provides a lateral shelf or ledge 7 across the transverse end of the car. An apron or wall in the form of a depending plate 8 is secured to the lower and outer vertical member of the Z-shaped plate and extends a distance below the same, as seen in Figure 3. The mast or brake shaft 9 passes through the shelf 7 and extends below the lower edge of the apron 8 and it is connected at its lower end with the winding gears. These winding gears are mounted within a housing consisting of a lower casting 10 and a top casting 11, the latter having a rectangularly-shaped horizontally disposed plate 12, which at its inner end is provided with a tapered extension 13 projecting back under the car. Adjacent its outer edge the plate 12 is provided with a strap or upstanding abutment 14 that is suitably braced or reinforced by transverse webs and which is disposed against the lower portion of the apron 8, so that the body of the plate 12 extends under the apron 8 and upon both sides of the latter.

In the fabrication of the car body a longitudinally extending side sill 15 has been provided, which is an angle bar of L-shaped section with the flange disposed lowermost. This sill, however, is not in a position, at its adjacent end to brace the gear housing by itself and I, therefore, provide an oblique L-shaped angle bar 16 that is placed with its lateral flange lowermost and resting upon the flange of the longitudinal sill 15, and said brace 16 extends forwardly and obliquely towards the center line of the car to and adjacent the apron 8, where it is secured to an L-shaped bracket 17 that is riveted or otherwise secured to the inner face of the depending apron 8. The disposition of this oblique brace 16 is such that the end of the tapered

portion 13 of the top plate 12 of the housing terminates below the lateral flange of the same and is secured to said flange by a rivet 18. The adjacent inner corner of the plate 12 is also below the flange of the brace 16 and is secured thereto by a rivet 19, while the opposite corner of this plate is below the longitudinal sill 15 and is secured thereto by the rivet 20.

10 From the foregoing, it will be seen the gear housing is securely braced against the pull of the winding chain or operating bar by means of the oblique brace 16 and the depending apron 8 is reinforced against 15 the stress which may be exerted by the abutment 14 which is bolted or riveted to the apron to provide a rigid structure.

What I claim is:

1. Means for mounting a brake gear, 20 comprising a car body provided with a depending member at the end thereof, a longitudinal side-sill, an obliquely disposed angle-bar connected at its forward end to the depending member at a distance from 25 the corner of the car body and secured at its opposite end to said longitudinal sill, and a gear housing, the upper member of which is provided with an inward extension secured to said oblique brace and has 30 an abutment arising in front of said depending member intermediate the adjacent end of the brace and the corner of the car body.

2. Means for mounting a brake gear, 35 comprising a longitudinal side-sill, an obliquely disposed angle-bar connected at one end to said sill back from the end of

the car and at its opposite end connected to a transverse member at the end of the car and spaced from the corner of the car, 40 a gear housing provided with a top plate the inner portion of which is tapered and secured to said angle-bar, and an abutment arising from said top-plate in front of the transverse member at the end of the car and 45 secured thereto.

3. Means for mounting a brake gear, comprising a longitudinal side-sill, a depending member extending transversely at the end of the car, an angle bracket secured to and projecting inwardly from the inner face of said depending member, an obliquely disposed angle-bar connected at its forward end to said angle bracket and at its opposite end secured to said side-sill, a gear 55 housing having a top-plate extending under said depending member and secured to said oblique angle-bar, and an abutment arising from said housing and secured to said depending member.

4. Means for mounting a brake gear, comprising a longitudinal side-sill, a depending member extending transversely at the end of the car, a brace disposed oblique to said sill and secured thereto, said brace at its opposite end connected to said depending member, and a gear housing connected to 60 said depending member and extended inwardly to and secured to said brace.

Signed at Chicago, in the county of Cook, 70 and State of Illinois, this 28th day of July, 1925.

SVEN JULIUS STRID.
